UNITED STATES PATENT OFFICE.

JAMES SCOTT PARRISH, OF RICHMOND, VIRGINIA, ASSIGNOR TO RICHMOND CEDAR WORKS, OF RICHMOND, VIRGINIA, A CORPORATION OF VIRGINIA.

ICE-CREAM FREEZER.

1,117,898.

Specification of Letters Patent. Patented Nov. 17, 1914.

Application filed February 9, 1911. Serial No. 607,652.

To all whom it may concern:

Be it known that I, JAMES SCOTT PARRISH, a citizen of the United States, and a resident of Richmond, county of Henrico, and 5 State of Virginia, have invented certain new and useful Improvements in Ice-Cream Freezers, of which the following is a full and clear specification, reference being had to the accompanying drawings, in which—
10 Figure 1 is a perspective view of the frame detached from the tub; Fig. 2 a vertical longitudinal section showing it attached to a tub; Fig. 3 a plan of a sheet metal blank from which the frame is struck
15 up or stamped and drawn.

The object of this invention is to provide an ice cream freezer gearing frame which may be stamped or drawn from practically a single blank of sheet metal, thereby producing a frame which shall be light in weight and have a maximum of strength for a given weight of metal, as more fully hereinafter set forth.

This invention has special reference to 25 that type of frame covered by patent to Rollman No. 1,011,247, dated December 12, 1911. The blank is shaped substantially as shown in Fig. 3, consisting of substantially 30 rectangular end portions *a* and a circular central portion *b*. The side edges of the blank are bent at right angles to the main portion of the blank, forming depending flanges *c* extending not only along the side edges of the end or bar portions of the blank 35 but also around the edges of the circular portion. The central circular portion is bent or drawn upwardly to form a curved dome portion *d*, and in the center of this dome portion a hole is cut and the metal 40 thereof is bent downwardly to form a depending annular flange *e* for the upper end of the hub or shaft of the upper gear wheel *f* of the gearing. This hole may be closed by a suitable plug *g* of metal, shown in
45 Fig. 2.

Extending transversely under the dome is a pair of bars *h*, for the reception of the lower end of the shaft of the gear *f* and for the cylindrical upper end of the freezer 50 can *i*, the bars *h* being fastened in any suitable manner. The flange *c* at one end of the frame is provided with a hole *j* for the reception of a suitable locking device, and the opposite end of the blank is cut out to form

two tangs which are curled to form hinge 55 members *k* which engage a suitable pintle carried by the hinge clip *l* fastened to the tub. At one side of the dome, the bar portion of the frame is slotted at intervals and the metal is bent downwardly to form depending flanges *m* extending longitudinally of the bar. Between these slotted portions the bar is left intact to form connecting cross pieces *n*. At the other side of the dome the metal is slotted and bent downwardly to form depending transverse ears or hangers *o* which are provided with alined holes which serve as supports or bearings for the drive shaft *p* of the gearing. Between two of the hangers *o* the bar is left 60 intact to form a cross connecting piece *q*, and at the end of the bar, adjacent to the hinge members *k*, another cross piece *r* is formed. In this manner a very light and well braced frame is formed from practically a single piece of sheet metal, and the formation of the device is such that it may be stamped and drawn to shape at but a single operation thus contributing greatly to cheapness of manufacture. 75

Having thus described my invention, what I claim as new and desire to secure by Letters Patent, is—

1. An integral frame for ice cream freezer gearings, consisting of a single sheet of 85 metal with a circular central portion, the longitudinal edges of said sheet being bent downwardly to form longitudinal flanges extending around said central portion and the full length of the frame, said central 90 circular portion being bulged upwardly to form a gearing dome, for the purpose set forth.

2. A frame for ice cream freezer gearings, consisting of a sheet of metal flanged along 95 its edges and having a central upwardly bulged portion, the metal at each side of the said central portion being slotted and bent downwardly to form depending flanges, for the purpose set forth.

3. A frame for ice cream freezer gearings, consisting of a sheet of metal flanged along its edges and having a central circular portion wider than the main body of the sheet and bulged upwardly to form a gearing 105 dome, the metal at each side of said dome being longitudinally and transversely slit at intervals, the tongues thus formed

being bent downwardly, thus forming longitudinal flanges and also transverse cross pieces.

4. A frame for ice cream freezers consisting of a sheet of metal approximately rectangular at its ends and approximately circular mid-way its ends, the circular portion being bulged upwardly to form a dome and the central top portion of this dome being bent downwardly to form an annular flange *e*, for the purpose set forth.

5. A frame for ice cream freezers consisting of a sheet of metal approximately rectangular at its ends and approximately circular mid-way its ends, the circular portion being bulged upwardly to form a dome and the central top portion of this dome being bent downwardly to form an annular flange.

e, and a disk *g* closing the opening formed by the bending down of said flange *e*.

6. A frame for ice cream freezer gearings, consisting of a sheet of metal flanged along its edges and having an upwardly bulged circular central portion, depending ears *o* at one side of said central portion, said ears being integral with the plate and formed by slitting the plate longitudinally and bending the intermediate portions downwardly.

In testimony whereof I hereunto affix my signature in the presence of two witnesses.

JAMES SCOTT PARRISH.
